Primary Examiner—Elizabeth A. Albert*Assistant Examiner*—Karen E. Eldridge Powers(74) *Attorney, Agent, or Firm*—Christensen O'Connor Johnson Kindness PLLC(57) **CLAIM**

The ornamental design of a pen, as shown and described.

DESCRIPTION

FIG. 1 is a front right perspective view of a pen showing my new design;

FIG. 2 is a left elevational view thereof;

FIG. 3 is a front elevational view thereof;

FIG. 4 is a right elevational view thereof; and,

FIG. 5 is a rear elevational view thereof.

The stippling shown in the drawings represents a texture on the surface of the pen.
